BRASSIÈRE

Maude C. Fridolph, Pasadena, Calif.

Application January 2, 1951, Serial No. 203,961

3 Claims. (Cl. 2—42)

1

This invention relates to a brassière.

The conventional brassière with which I am familiar usually encircles the body in a generally horizontal plane, that is, the bottom edge of the brassière extends around the body in a substantially straight horizontal line just below the bust and at the lower ends of the shoulder blades. With brassières of this type the weight of the bust has a tendency to cause the cups at the front of the brassière to sag and to thereby cause the back of the brassière to slip upwardly toward and above the shoulder blade line where the circumference of the body becomes greater. This causes much discomfort to the wearer, since the upward movement of the brassière back causes a tightening of the brassière under the bust line in the front.

It is an object of this invention to provide a brassière which gives the proper uplift support to the bust and which is designed to remain anchored on the body in a comfortable position.

More specifically, the invention contemplates a brassière the back portion of which extends around the side back portions of the wearer's body in an arcuate downward direction conforming to the natural body contour and extends across the small of the wearer's back well below the shoulder blades at the center back of the brassière. By shaping the back portion of the brassière in this manner, the brassière fits around a portion of the body below the shoulder blades which is of smaller circumference than at a horizontal section just below the bust line and resists any upward movement in the back which would tighten the lower front edge of the brassière under the bust line. The arcuate shape of the back portions of the brassière serves to anchor the brassière in a comfortable position on the wearer's body.

In the drawings:

Fig. 1 is a side view of the brassière on a wearer;

Figs. 2 and 3 are front and rear perspective views of the brassière on a wearer;

Fig. 4 is a view of the brassière in the open, flat condition;

Fig. 5 is a front view of a modified form of brassière in the open flat condition; and

Fig. 6 is a front view of the band adapted to be used with a brassière having a straight or slightly curved front edge to convert it to the type of brassière disclosed in Figure 5.

Referring to the drawings and particularly to Fig. 4, a typical brassière embodying the present invention comprises a front portion generally designated 10 which is preferably fashioned as

2

two similarly shaped members 12 and 14 which are connected together at the center of the brassière by a narrow elastic gore 16. The members 12 and 14 are provided with central seams 18 and are shirred as at 20 to form a pair of breast-receiving cups 22 the upper portions of which are triangular or otherwise suitably shaped and have apices 24 or upper edges on which the brassière shoulder straps 26 are anchored at the front of the brassière. On their inner faces, front sections 12 and 14 may have reinforcing panels 28 sewed thereto which support the bust in the desired contour.

Along its upper and lower edges the front portion 10 may be hemmed as at 30 and 32, respectively, with a suitable tape, the lower edge 32 preferably being arcuate in shape so that it curves downwardly from the elastic gore 16 to each end of the front portion 10. The front portion 10 is dimensioned such that, at each end, it terminates along a generally vertical line below the wearer's armpits. A pair of similarly shaped back members 34 or straps are sewed to the side edges of front portion 10 as at 36. The back portions 34 have a hemmed lower edge 38 which extends arcuately in a downward direction as a continuation of the arcuately contoured lower edge 32 of front portion 10.

The portions of the lower edges which extend around the side back portions of the wearer's body, that is, the edge portion between points *a* and *b* are preferably shaped as an arc of a true circle. I have found that when the lower edge of the back portions 34 of the brassière is shaped in this manner, the back portions lie flat against the body and the lower edges thereof follow the natural body contour in this region. For a size 32 brassière, I have found that the edge 38 between the points *a* and *b* should preferably describe an arc having a radius of approximately 6½ inches. The upper edges 40 of the back portions 34 are shaped generally to provide the back portions 34 with a gradually decreasing vertical dimension towards the free ends of the back portions. At their free ends, the back portions 34 have small elastic gores 42 sewed thereto which members are provided with fastening means 44, such as hooks and eyes, for securing the ends of the brassière together at the center back of the wearer. If desired, the entire back may be of elastic. The shoulder straps 26 are attached to the upper edge of rear portions 34 as at 50 and 52.

Referring to Fig. 1, it will be observed that the rear portions 34 are shaped such that, when the brassière is on the wearer, these portions extend

arcuately downwardly around the side back portions of the wearer's body with the upper edge of the brassière at the center back disposed at a lower level than the lower edge of the brassière at the front. The lower edges 32 and 38 extend along a curved line corresponding generally with the rib line of the wearer so that the elastic gores 42 connect together at approximately the small of the back. The lower edge of the brassière therefore encircles a portion of the wearer's body that has a circumference less than the circumference of the body at a horizontal section at or over the shoulder blades just below the bust line. In other words, the body becomes increasingly greater in circumference in a direction upwardly from the lower edge of the brassière. Inasmuch as the back portions 34 converge downwardly toward the small of the back, they are disposed below the shoulder blades and provide a V-shaped structure, which lies smoothly against the back of the wearer and, despite its flexibility, resists straightening. The need for the brassière to expand in order to slide up, and the resistance of the V-shaped back to straightening, combine to anchor the brassière in the position illustrated in Figs. 1, 2 and 3.

When a brassière of my construction is laid flat in the opened condition such as is illustrated in Fig. 4, the lower edge of the brassière generally describes a semi-circle. This is in direct contrast to conventional brassières the lower edges of which, when laid flat, describe a straight line or a line which is only slightly curved at most.

The front of the brassière need not be of the type described above. Any standard brassière can be adapted readily to the curved band type, as illustrated in Figs. 5 and 6. In this type of brassière the front portion 50 including the cups 51 and 52 has a straight or nearly straight lower edge 53 and substantially straight, tapered back straps or bands 54 and 55. To adapt this type of brassière, a band 56 is secured to the lower edge 53 of the brassière. The band 56 may be formed of non-elastic fabric or elastic fabric or part elastic and part non-elastic fabric. The band 56, as illustrated, is formed of non-elastic fabric and has a substantially semi-circular lower edge 57 like that described, and a straight upper edge 58. One or both of the ends of the band may have an elastic gore 59 thereon which is provided with fasteners 60, for example, hooks, for cooperation with eyes 61 on the other edge 62. If the band 56 is formed of elastic fabric, the gore 59 may be formed of non-elastic fabric or may be omitted entirely. In this latter form, the band 56 is made long enough to compensate for the absence of the gore or gores 59. The band 56 extends, when fastened, almost to the waist-line thereby giving the effect of a long-line brassière in back and a short-brassière in front. The band 56 anchors the brassière firmly at the waist-line and gives support to the back without constricting the dia-

phragm as with the ordinary long-line brassière.

It will thus be seen that I have provided brassières which are designed such that they remain relatively firmly anchored on the wearer's body in a comfortable position. Furthermore, the downwardly curved lower edge of the brassière prevents the back portion of the brassière from creeping up the wearer's back. This construction prevents the tendency for the busts to sag and substantially eliminates the tightening of the brassière across the front of the wearer's body just below the bust line.

I claim:

1. A brassière comprising a front portion including a pair of spaced apart cup sections, side bands extending outwardly and downwardly from opposite ends of said front portion, and means to secure the outer ends of said side bands together, said front portion and said side bands having lower edges which describe substantially a semi-circle when the front portion and side bands are laid flat in an open condition.

2. A brassière comprising a front portion having a pair of spaced cup sections and having a generally concavely curved lower edge which extends downwardly from its center to its ends, and a pair of side bands connected to opposite ends of said front portion and extending outwardly and downwardly therefrom, one from each of the opposite ends of said front portion, said side bands having lower edges extending arcuately downwardly towards the free ends thereof and forming a continuation of the lower edge of said front portion to describe therewith substantially a semicircle when the garment is laid flat in an opened condition.

3. A brassière comprising a front portion including a pair of spaced cup sections, back portions extending outwardly from opposite ends of said front portions, said front portion and back portions having substantially aligned straight lower edges, a band secured to said lower edges, said band having a substantially straight upper edge secured to the straight lower edges of said front and back portions and a substantially semicircular lower edge and fastening elements at its ends for securing said band at the back of the wearer from about the middle of the back substantially to the waistline.
